UNITED STATES PATENT OFFICE.

WILSON E. SYMONS, OF PITTSBURG, KANSAS.

LOCOMOTIVE-TRUCK.

No. 813,255.

Specification of Letters Patent.

Patented Feb. 20, 1906.

Application filed July 6, 1905. Serial No. 268,377.

To all whom it may concern:

Be it known that I, WILSON E. SYMONS, a citizen of the United States, residing at Pittsburg, in the county of Crawford and State of Kansas, have invented a new and useful Locomotive-Truck, of which the following is a specification.

This invention relates more particularly to improvements in four-wheeled leading-trucks 10 of locomotives, though there are certain features of novelty not necessarily limited thereto, as will be apparent to those skilled in the art.

One of the principal objects is to provide a 15 main frame cast in one piece, thereby greatly reducing the number of parts to be fitted, and consequently reducing the cost of manufacture and maintenance, while increasing the strength and durability of the truck.

Another object is to provide a structure of 20 the above character that will permit the application of the wheels and axles without the necessity of jacking up the truck from the rails a distance equal to the length of the 25 jaws or pedestals.

A still further object is to improve the various details of construction in order to secure strength and durability in connection with simplicity.

One embodiment of the invention is illustrated in the accompanying drawings and is described in the following specification. An inspection of the claims hereto appended will show that the invention is not limited solely 35 to this embodiment.

In the drawings, Figure 1 is a plan view of the truck. Fig. 2 is a side elevation of the same, the wheels on the nearer side being removed. Fig. 3 is an end elevation of the 40 truck. Fig. 4 is a longitudinal sectional view therethrough. Fig. 5 is a side elevation of the main frame, together with the separate pedestals and boxing-shoes detached. Fig. 6 is a cross-sectional view through the main 45 frame and equalizer-bars. Fig. 7 is a sectional view on the line 7 7 of Fig. 6. Fig. 8 is a detail sectional view on the line 8 8 of Fig. 5. Fig. 9 is a top plan view of one of the 50 pedestals. Fig. 10 is a side elevation of the same.

Similar reference-numerals designate corresponding parts in all the figures of the drawings.

In the embodiment illustrated a main 55 frame is employed that is of a single piece and of cast-steel. This main frame consists

of side beams 11, end bars 12, connecting the ends of said side beams and integral therewith, and an intermediate transom 13, connecting the central portions of the side beams 60 and formed integral with the same. Each side beam, as particularly shown in Fig. 8, consists of an upright web 14, provided with inset upper and lower flanges 15 and 16, formed upon the upper and lower margins of 65 the web. The flanges 15 and 16 terminate at the ends of the side beams and the end bars 12 are inverted substantially L-shaped in cross-section, consisting of angularly-disposed flanges 17 and 18, the former of which 70 constitute upright webs, and the flanges 18 projecting outwardly.

The transom 13 consists of a central bearing or female casting having a tubular bowl-shaped body 19 with a circular top or bearing-plate 20, carrying an upstanding peripheral flange 21, and having a central bolt-receiving opening 22. On opposite sides of this bearing extend webs 23, integrally joined to the bowl-shaped body and to the upright 80 webs 14 of the side beams, as illustrated in Fig. 6. Lower flanges 24, extending on opposite sides of the webs 23 and located longitudinally along their lower margins, are integrally connected to the lower flanges 16 of 85 the side beams, while upper oppositely-projecting flanges 25, located along the upper edges of the webs 23, extend from the annular flange 21 to the upper flanges 15 of the side beams, these flanges 25 tapering in opposite 90 directions, as shown in Fig. 1.

Depending from the end portions of the side beams are integral pedestals consisting of bearing-plates 26 and brace-webs 27. The outer sides of the plates 26 are provided contiguous to their upper ends with recesses 28. Coöperating with these integral pedestals are other pedestals 29, consisting of bearing-plates 30 and bracing-webs 31, said pedestals also having tops 32, that bear against the under sides of the side beams 11 outside the integral pedestals and being secured thereto by bolts 33, which pass through said tops 32 and through the lower flanges 16 of the side beams. The inner sides of the pedestals 29 100 are provided with seats 34 similar to the seats 28 of the integral pedestals. These seats are adapted to receive similar-shaped lugs 35, formed upon the upper ends of shoes 36, that detachably fit against the inner faces 110 of the pedestals and are held in place by binders 37, bolted, as shown at 38, to the

lower ends of the coöperating pedestals and have thickened intermediate portions 39, which fit between the lower ends of the shoes and hold the same in position.

- 5 Journal-boxes 40, fitted between the pedestals, operate against the shoes, and associated with said journal-boxes are the usual journal-box cellars 41. Mounted in the journal-boxes are axles 42, carrying wheels 43. 10 Supported by the journal-boxes 40 are equalizing-bars 44, which bars are substantially bowed and are provided with downturned terminals 45, seated on and in the tops of the boxes 40. Each of the equalizing-bars 15 consists of an upright web 46, having offset upper and lower marginal flanges 47. A pair of the equalizing-bars are associated with each side beam 11 of the main frame, being located on opposite sides of the same, as illustrated in 20 Fig. 1, the bars tapering toward their ends, as shown. Hanger-stirrups 48 are pivoted by means of bolts or pins 49 to and between the equalizer-bars of each set, and supported by the hanger-stirrups are springs 50, which 25 springs bear against the under sides of the side beams 11 at the juncture of the transom 13 therewith.

The truck above described is very strong and durable and yet is composed of very few 30 parts, the main frame, including certain of the pedestals, being of one piece which can be readily cast and requires but little machine-work when the other parts are assembled therewith. At the same time by having the 35 outer pedestals detachable the axles and wheels can be readily applied without the necessity of jacking the entire truck-body from the rail a distance equal to the height of the pedestals. The various parts are, further, 40 simple in structure, yet very strong to withstand the necessary jars and strains. At the same time these parts are light in weight and can be readily manufactured.

From the foregoing it is thought that the 45 construction, operation, and many advantages of the herein-described invention will be apparent to those skilled in the art without further description, and it will be understood that various changes in the size, shape, proportion, and minor details of construction 50 may be resorted to without departing from the spirit or sacrificing any of the advantages of the invention.

Having thus described my invention, what 55 I claim as new, and desire to secure by Letters Patent, is—

1. In a truck of the character described, a single-piece main frame comprising channel side beams composed of upright webs having 60 longitudinally-disposed upper and lower substantially horizontal marginal flanges, and substantially L-shaped cross-bars, each consisting of an upright web and a single longitudinally-disposed substantially horizontal 65 marginal flange.

2. In a truck of the character described, a single-piece main frame comprising channel side beams composed of upright webs having longitudinally-disposed upper and lower substantially horizontal and inwardly-extending 70 marginal flanges leaving substantially smooth outer sides to the beams, and cross-bars connecting the side beams, each of said cross-bars being substantially L-shaped in cross-section and comprising an upright bar and 75 a single horizontally-disposed substantially horizontal outstanding marginal flange.

3. In a truck of the character described, the combination with a main frame including a side beam having an inwardly-extending 80 longitudinal flange, of a pedestal fitted against the under side of the beam, and fastening means for the pedestal passing therethrough and through the said inwardly-extending longitudinal flange. 85

4. In a truck of the character described, the combination with a main frame including a side beam having an inwardly-extending longitudinal flange, said flange having an integral pedestal depending therefrom, of detachable pedestals coacting with the integral pedestal and fitted against the under side of the flange, and fastening-bolts for the detachable pedestals, said bolts passing through the 90 said inwardly-extending longitudinal flange. 95

5. In a truck of the character described, the combination with a main frame including a side beam provided with an offset flange along its lower margin, of a pedestal fitted against the flange, and bolts engaging the pedestal and passing through the flanges for securing the pedestal to the beam. 100

6. In a truck of the character described, the combination with a main frame including a side beam provided with an offset flange 105 along its lower margin, of an integral pedestal depending from the beam, another separate pedestal fitted against the flange and coöperating with the integral pedestal, and bolts engaging the latter pedestal and passing 110 through the flange for securing said pedestal to the beam in coöperative relation to the integral pedestal.

7. In a truck of the character described, the combination with a main frame including 115 a side channel-beam composed of an upright web and inset upper and lower flanges, of depending integral pedestals carried by the side beam, detachable pedestals located outside and coöperating with the integral pedestals, 120 said detachable pedestals bearing against the lower side of the side beam, and means for securing the detachable pedestals to the side beam.

8. In a truck of the character described, the combination with a main frame comprising side beams provided with upper and lower inset flanges and integral-end bars connecting the ends of said side beams, of depending inner pedestals carried by the side 130

- beams, detachable outer pedestals coöperating with the integral pedestals and fitted against the lower flanges of the side beams, bolts connecting the detachable pedestals 5 and the flanges, and binders connecting the associated integral and detachable pedestals.
9. In a truck of the character described a main frame including side beams and end bars connecting the ends of the side beams 10 and being substantially inverted - L-shaped in cross-section.
10. In a truck of the character described a single-piece main frame comprising side channel-beams and substantially L-shaped end 15 bars connecting the same and integral therewith.
11. In a truck of the character described, a single - piece main frame comprising side beams of upright webs and offset upper and 20 lower flanges, substantially L-shaped end bars connecting the ends of the side beams and formed integral therewith, and depending integral pedestals carried by the lower flanges of the side beams, in combination 25 with detachable pedestals fitted against said lower flanges and coöperating respectively with said integral pedestals, and bolts for securing said pedestals and lower flanges of the side beams together.
- 30 12. In a truck of the character described, a main frame including side beams and a transom extending between the side beams, said transom comprising an upright web having offset longitudinally - disposed marginal flanges.
- 35 13. In a truck of the character described, a main frame including side beams, and a transom extending between the same, said transom comprising an upright central web, and 40 oppositely - projecting longitudinally - disposed marginal flanges located on opposite sides of the web.
14. In a truck of the character described, a main frame including side beams and a transom 45 extending between the same, said transom having a central bearing or female casting, upright webs located on opposite sides of the bearing or female casting and connecting the same with the side beams, said webs 50 being provided with oppositely - projecting longitudinally-disposed marginal flanges.
15. In a truck of the character described, a main frame including channel side beams and a transom connecting the intermediate portions 55 of the side beams and made integral therewith, said transom having a central bearing or female casting, upright webs connecting the bearing or female casting and side beams, and oppositely-projecting longitudinally-disposed upper and lower flanges 60 located along the margins of the webs.
16. In a truck of the character described, a main frame comprising side beams, each of 65 said side beams consisting of an upright web and inwardly - extending upper and lower
- marginal flanges, end bars made integral with the side beams and connecting the ends of the same, said bars consisting of angularly-disposed flanges, and a transom also integral with the side beams and located between the 70 end bars, said transom having a central bearing, upright webs between the bearing and the side beams, and marginal flanges carried by the upper and lower portions of the webs and connecting the central bearing and said 75 side beams.
17. In a truck of the character described, the combination with a single-piece main frame comprising side beams, end bars, and a transom, each of said elements having an upright web and offset marginal flanges, of depending pedestals carried by the side beams, certain of said pedestals being integral therewith, others being separate therefrom, bolts 80 securing the separate pedestals to the side 85 beams, binders connecting the lower ends of coöperating pedestals, and journal-boxes located between the pedestals.
18. In a truck of the character described, the combination with a main frame including 90 side channel-beams, of journal-boxes mounted on the side beams, channel equalizer-bars located on opposite sides of the side beams and supported at their ends on the journal-boxes, and springs connected to the equalizer- 95 bars and side beams.
19. In a truck of the character described, the combination with a main frame including 100 side beams composed of upright webs and marginal flanges, of journal-boxes mounted 105 on the side beams, equalizer-bars located on opposite sides of the side beams and supported at their ends on the journal-boxes, said bars also comprising upright webs and marginal flanges, spring-hangers suspended from 110 the equalizer-bars and located between the same, and springs supported on said hangers and engaging the side beams.
20. In a truck of the character described, the combination with a single-piece main 110 frame including channel side beams having depending integral and detachable pedestals, of journal-boxes mounted between the pedestals on the side beams, bowed equalizer channel-bars located on opposite sides of the side 115 beams and supported at their ends on the journal-boxes, and springs associated with the equalizer-bars and side beams.
21. In a truck of the character described, the combination with a main frame including 120 side beams, of journal-boxes mounted on the side beams, equalizer channel-bars located on opposite sides of the side beams and supported at their ends on the journal-boxes, and springs interposed between the equalizer- 125 bars and side beams.
22. In a truck of the character described, the combination with a main frame, of journal-boxes mounted thereon, and an equalizer-bar comprising a web and offset longitudinal 130

flanges, said bar having downturned terminals seated on the journal-boxes, and said flanges having their terminal portions tapered and terminating at the downturned ends of the bar.

23. In a truck of the character described, the combination with a main frame including a side beam, of journal-boxes mounted thereon and projecting on opposite sides of the same, and equalizer-bars located on opposite sides of the side beam and bearing on the boxes, said bars having the faces that are opposed to the beam substantially flat and having outstanding flanges on their opposite faces, which flanges taper toward their ends.

24. In a truck of the character described, an equalizer-bar tapering toward its ends and comprising a web having offset flanges.

25. In a truck of the character described, a bowed equalizer-bar having downturned ends, said bar comprising a web having upper and lower offset marginal flanges.

26. In a truck of the character described, the combination with a main frame including side beams, of pedestals carried by the side beams and having recesses in their upper portions below the side beams, shoes fitted upon

the pedestals and having lugs that engage in the recesses, and binders connecting the lower ends of the pedestals and engaging the lower ends of the shoes.

27. In a truck of the character described, the combination with a main frame including a side beam, said side beam being provided with an integral pedestal depending therefrom and said pedestal having a recess in its upper portion below the side beam, of a detachable pedestal secured to the side beam and coacting with the integral pedestal, said detachable pedestal also having a recess in its upper portion, shoes fitted upon the inner opposing sides of the pedestals and having portions engaged in the recesses thereof, and a binder connecting the lower ends of the pedestals and engaging the lower ends of the shoes to retain the said portions of the shoes in the recesses.

In testimony that I claim the foregoing as my own I have hereto affixed my signature in the presence of two witnesses.

WILSON E. SYMONS.
